UNITED STATES PATENT OFFICE.

ANDREW C. CUNNINGHAM, OF NORTH CHICAGO, ILLINOIS.

AGITATOR.

1,141,528.

Specification of Letters Patent.

Patented June 1, 1915.

Application filed January 18, 1915. Serial No. 2,847.

To all whom it may concern:

Be it known that I, ANDREW C. CUNNINGHAM, a citizen of the United States, residing at North Chicago, county of Lake, and 5 State of Illinois, have invented certain new and useful Improvements in Agitators; and I do hereby declare the following to be a full, clear, and exact description of the invention, such as will enable others skilled in 10 the art to which it appertains to make and use the same.

This invention relates to agitators, and has for its object to provide a device of this kind having the novel features of construction hereinafter set forth.

One form of the invention is illustrated in the accompanying drawing, in which—

Figure 1 is a side elevation of the improved agitator illustrating one method of operating the same; Fig. 2 is a side elevation, partly in section, of the agitator in combination with mechanical actuating means; and Fig. 3 is an underneath view of the agitator looking in the direction of the arrow 25 in Fig. 1.

In the preferred form, the agitator comprises three elements so connected as to form a structure having a substantially triangular cross section. Each of these elements, which 30 are indicated at 1, 2 and 3 in the drawing, preferably consists of a flat spiral coil of stiff self-sustaining wire, the outer end of which extends away from the coil to constitute a stem portion capable of being connected to a suitable handle or other actuating device. The stem portions of the elements 1, 2 and 3 are indicated at 4, 5 and 6, respectively.

The flat spiral coils are disposed in triangular or other relation and connected at 40 their lateral edge portions by any appropriate means. This may be accomplished by soldering the adjacent portions of the coils together, as indicated at 7. When the 45 elements are assembled, they are canted out of the vertical plane, so that each element will be inclined relative to the longitudinal axis of the agitator, and so that the combined elements present the form of a triangular pyramid, the apex of which is constituted by the diverging stem portions of the coils. The stem portions diverging at the apex of the pyramidal structure so formed are brought together, and preferably

slightly interlaced, as clearly shown in the drawing, and then connected to a suitable handle 8, (Fig. 1). Obviously, the stem portions 4, 5 and 6 may extend upwardly as far as desired, and may themselves constitute the handle.

The handle 8 permits the agitator to be used in any desired manner, but as the device is primarily intended to be rotated about its longitudinal axis, a suitable extremital portion 9 is associated with the handle, which may be engaged between the palms of the operator's two hands and rotated by moving the hands back and forth relative to each other, in an obvious manner, as indicated in Fig. 1.

It may be desirable to mount the agitator in a suitable actuating device to facilitate rotation of the same, and for this purpose, a bracket 10 may be provided, (Fig. 2), having a bearing portion 11 which receives 75 the stem of the agitator. The stem is rotatably mounted in the bearing 11 and rigidly carries a pinion 12 engaging with a gear 13, rotatably mounted on the bearing 11. A handle 14, associated with the bearing 11, constitutes means for holding the stationary part against movement, while a handle 15, associated with the gear 13, provides means for rotating the gear 13, pinion 12, and hence the agitating device. In 80 the present instance, the bracket 10 is mounted upon the top 16 of a suitable container 17 adapted to receive the material to be agitated, and the stem of the agitator projects through said top 16, as shown at 18. It will 85 be understood, however, that such a mounting of the agitator is merely exemplary, as the agitator may be actuated in any manner whatsoever.

The three elements associated in the manner above described result in a strong, rigid and durable construction, the elements of which may be cheaply made and readily assembled.

Although the elements are shown in the drawing as sloping outwardly from the top to the bottom, it is obvious that the inclination of the elements in this specific direction is not necessary, as the elements, if so desired, may be inclined in the opposite direction. Furthermore, the exact construction of the elements is immaterial, as the wire at the coils may be bent to numerous different

shapes, the spiral shape illustrated being merely exemplary.

The agitator may be used for agitating, pulverizing, aerating and intimately associating fluids, liquids, semi-fluids, or viscous substances. By the use of the improved agitator, coarse or fine solids may be intimately mixed with liquids or fluids, and soluble solids may be pulverized and mixed with liquids.

The novel construction of the agitator causes a violent agitation of the substance acted upon, as the rotation of the triangularly arranged elements throws the particles of the substance outwardly, and the inclination of the elements causes a circulation of the agitated substance in either an upward or downward direction. This violent agitation of the substance especially adapts the agitator for use in mixing solids and fluids which are only mixed with great difficulty by other devices.

Obviously, the time required to intimately mix or sufficiently agitate the treated substance will depend upon the speed of rotation of the agitator, and this may, of course, be controlled at will by the operator.

The agitator shown in the drawing is designed especially for light work, such as mixing and agitating foodstuffs and the like, but obviously, the device may be made of much greater size and used for relatively heavy work, and any suitable actuating and

supporting mechanism may be employed for rotating the same.

35

What I claim is:—

1. An agitator composed of a plurality of elements each of which comprises a continuous length of wire, one end of which is bent into a plurality of convolutions lying in the same plane to form a coiled agitating portion, the coiled portions so formed being grouped about the longitudinal axis of the agitator and connected at their adjacent lateral edges, the uncoiled portions of the several wires being extended away from the coiled portions, for the purpose described.

45

2. An agitator composed of a plurality of elements each of which comprises a continuous length of wire, one end of which is bent into a plurality of convolutions lying in the same plane to form a coiled agitating portion, the coiled portions so formed being grouped about the longitudinal axis of the agitator and inclined with respect thereto 50 and connected at their adjacent lateral edges, the uncoiled portions of the several wires being extended away from the coiled portions, for the purpose described.

55

In testimony whereof I affix my signature, in presence of two witnesses.
